UNITED STATES PATENT OFFICE.

EDWARD E. THRESHER, OF AKRON, OHIO.

ARTIFICIAL BIRD TARGET.

Application filed December 4, 1919. Serial No. 342,436.

To all whom it may concern:

Be it known that I, EDWARD E. THRESHER, a citizen of the United States, residing at Akron, in the county of Summit and State of Ohio, have invented new and useful Improvements in Artificial Bird Targets, of which the following is a specification.

The primary object of the invention resides in the provision of an artificial live-bird target designed to take the place of live birds and dispense with the cruel shooting of such birds for sport, and has particular reference to what is known as live bird trap-shooting, wherein the artificial live bird target is made to resemble a live bird in shape, appearance, and flight as perfectly as human skill can imitate nature and is briefly described as follows:—The body is made in two parts of sheet steel, each showing half of the head, neck, body, one wing and tail and are hinged together on the under portion of the body, and the metal between the wings is removed making a slot large enough to receive the locking device on the under portion of the carrier plate; the locking device is inclosed within a steel casing which is an eighth of an inch shorter than the slot to admit of free entrance and also of a lateral movement of the body on the suspending part of the lock; and said casing supports on each side a hinged expensible leaf which when locked impinges on the curved surface of the inner wall of the body. The base plate of the carrier has lips that extend a $\frac{1}{2}$ inch beyond the ends of the slot making it impossible to insert in the slot more than the locking portion of the carrier: The carrier supports an upper casing which houses a small sheave or trolley wheel and is slotted to receive the suspending traveling wire cable on which the trolley wheel rides and the outer ends of said casing is slotted to receive and fasten the ends of the suspending traveling wire cable as herein-after described.

A further object of the invention includes a novel method of locking and supporting the bird in a flying position by raising the body until the lock casing is submerged

in the slot between the wings and the projecting lips of the carrier plate rest on the flanges at each end of slot, then turning the thumb nut forces the slide bolt heads under said flanges thus locking the body between the carrier lips and said heads and holding it in that position until hit with missile shot.

The novel and essential features of said lock are the arms of the connecting rods (called triggers) and their action on the hinged leaves, when the thumb nut is turned to lock the bird these triggers are forced out through the trigger slots and press the hinged leaves against the inner wall on each side of the bird's body so that the lower corners of the leaves impinge on the curved inner surface thereof thereby creating a double leverage on the triggers, viz: one by the leverage of the leaves on the triggers and another by the leverage of the body on the leaves; and further improvements contemplate the provision of an adjustable connection at the head whereby the pressure of the bird sides and leaves on the triggers may be regulated so perfectly that the force of one or two shot pellets hitting the bird anywhere will trip the triggers and cause the bird to fall and hang suspended by the tongue and register a kill. Another very important feature lies in the impingement of the leaves on the body at two points in front and two at back. This impingement not only steadies and braces the body in the locked position but also gives the most perfect kill possible to obtain even when hit anywhere on the side, head, wing or tail and also because the lateral movement of the body if hit in front or behind will trip the lock just the same.

The invention further includes certain improvements that will be evident from the detailed description thereof over the patent granted to E. E. Thresher upon artificial bird target, No. 1,075,518, patented Oct. 14, 1913.

With the above and other objects in view, this invention consists in the novel form, combination and arrangement of parts here-

in fully described and shown in the accompanying drawings, wherein like reference characters indicate similar parts throughout the several views.

5 In the drawings,

Figure 1 is a side elevational view of an artificial bird target constructed in accordance with the present invention, the same being partially broken away,

10 Figure 2 is a top plan view thereof, a portion of the casing being broken away,

Figure 3 is a fragmentary view, partially in section of the bird suspending device with the bird suspending arm in collapsed position.

15 Figure 4 is a cross sectional view taken transversely of Figure 3 and,

Figures 5 and 6 are bottom plan views of the bird holding mechanism in released and 20 set positions respectively.

Broadly, the present invention contemplates certain improvements over the patent, and has particular reference to the manner of suspending the target bird upon a line 25 wire as well as the provision of protecting plates enclosing the releasing mechanism. As contrasted with the patent above mentioned, the ends of the suspending wire are connected to the upper end of the carrier 30 casing containing the suspension wheel, which method of mounting the bird prevents undue vibration during the traveling movement over the wire with the obviation of a consequent accidental release of the 35 bird. The protecting plates enclosing the operating mechanism receive the shock from the sides of the bird for releasing the bird holding mechanism that is contrasted with a direct engagement of the operating mechanism with the sides of the bird in the above 40 mentioned patent, and other novel details of construction and improved steps in the operation of the device will be apparent from the detailed description.

45 Referring more in detail to the construction herein disclosed, and particularly to Figures 1 and 2, there is provided an artificial bird embodying side sections 1 simulating the body of a bird and hinged at the bottom edges thereof as at 2, tail sections 3 being carried by the rear end of the body while neck and head sections 4 are carried by the other end of the body. Upstanding wings 5 representing the bird in flight are carried by the body sides 1 and the bird is caused to assume the position shown in Figures 1 and 2 by a pin 6 extending through the head 4 of the bird at the eye portion and being retained therein by cotters as illustrated. An important feature of the present invention includes the mounting of one or more washers or fillers 7 upon the projecting ends of the pin 6 inwardly of the cotters whereby the sides of the bird may be caused 60 to assume an initial position at various dis-

tances apart to compensate for cartridges of different calibers, and for other purposes to hereinafter appear.

As illustrated in Figure 3, the bird 1 is mounted upon a suspension wire 8, which is 70 supported in any suitable manner, such as over spaced sheaves not shown, for allowing free travel of the same and having the ends thereof connected as at 9 to arms 10 upon a casing 11, the lower side of the suspension 75 wire 8 being unobstructed and passing through aligned openings 12 in opposite sides of the casing 11 and beneath the sheave 13, which sheave rides upon the wire 8 for suspending the bird as will at once be evident. 80

Depending arms 14 are carried by the housing 11 and are connected to the opposite ends of a plate 15, having depending side walls 15^a shown in Figures 5 and 6 which plate has slidably mounted upon the 85 lower face thereof oppositely moving slides 16 between the side walls 15^a, the slides having heads 17 upon the outer projecting ends thereof, each head having lateral extensions 17^a guided in the bifurcated ends 90 of the plate walls 15^a. Side plates 18 are swingingly supported as at 19 to opposite longitudinal edges of the plate 15, as shown in Figs. 1, 3 and 4. These side plates 18 are provided for the purpose of protecting the 95 mechanism positioned therebetween, and which will be described in detail hereafter, from any stray shots accidentally fired at the device after it has been stripped.

A depending housing 20 is carried by the 100 plate 15 and has a pivotal connection 21 at its lower side with a link 22, which link is connected at its opposite end to the pin 6 at the head of the bird with said link lying in the space between the neck and head sections 4 of the bird. As illustrated in Figures 1 and 2, the body portions 1 of the bird are provided with flanges 23 that extend rearwardly from the head and neck portions 4 and forwardly from the tail portions 110 3 and are adapted to be positioned on a plane slightly over the heads 17 of the slides 16 and to be engaged by the same when they are projected to hold the birds in the flying position illustrated in Figure 1. The slides 115 16 are maintained distended by the spring and lever devices as illustrated in Figure 6, a disk 24 carried by a stem projecting upwardly through the plate 15 and being operable by a thumb nut 25 upon the upper end of the stem, while diametrically opposite levers 26 are pivoted as at 27 to opposite sides of the disk 24 with the other ends of said levers 26 pivoted upon pins 28 carried by the slides 16. Oppositely directed angle 120 arms 29 are carried by the levers 26 with the outer ends thereof, when the slides are extended, projecting through side slots in the housing as shown in Fig. 4, a spring 30 connecting the pivot pins 28 of said levers 125 310

and holding the pivot points 27 slightly moved to opposite sides of the longitudinal axis of the slides 16 so that the angle extensions 29 are maintained in projected condition through the side walls of the housing.

The opposite sides of the plate 15 have hinged thereto a pair of side plates 18 freely depending from the upper edges of the housing and lying outwardly of the angle arms 29 to be engaged by said arms when extended, and positioned intermediate the arms and sides 1 of the bird body to operate the spring and lever releasing devices and to protect the same from contact with the sides 15 of the bird body.

With the device as above described, where the sheave 13 travels over the suspension wire 8 with the ends of the wire connected as at 9 at points above the extension sheave 13, liability of vibration or swaying is greatly reduced due to the bracing effect afforded by the connection of the wire at the points 9 spaced from the plane of support at the lower side of the sheave 13 and on the opposite side thereto to the weight of the body and mechanism with a consequent elimination of a possible accidental collapse of the bird. When a shot or other object strikes the side 1 of the bird, the same is moved upon its hinge connection 2 for engagement with the plate 18 to shift the angle extensions 29 of the levers 26 with the subsequent operation of the spring to move the arms from the position shown in Figure 6 to the position illustrated in Figure 5 and thus for a retraction of the slides 16 and heads 17, to release the heads 17 from the inwardly directed flanges 23 upon the body portions of the bird and to permit the bird to collapse and be suspended by the link 22 connecting the head of the bird with the depending housing 20, and when so arranged the spring 30 maintains the slides 16 retracted. When it is desired to reset the bird, the body portions 1 and 2 are moved upwardly to position the flanges 23 slightly above the slide heads 17 and by operating the thumb nut 25, the slides are moved to reset the levers and arms 26 and 29 for retaining the bird in a horizontal position. With this device, it will therefore be seen that the operating mechanism is protected from direct contact with the movable sides of the bird and that the releasing tensioned levers are shifted by the enclosing protecting plates 18. Also, by placing washers of different widths upon the pins 6, the sides of the bird may be normally held at greater or lesser distances apart so that the operating levers will be in their set position at points nearer to or spaced from the longitudinal axis of the operating mechanism, thereby to provide a target which may be initially set for operation by cartridges of different calibers.

When it is desired to secure the bird target

in its set position, the depending housing 20 with its swingingly supported side plates 18 are positioned between the side sections 1, which constitute the body of the target, and the thumb nut 25 is turned to position the heads 17 of the slides 16 beneath the flanges 23. The device will be retained in this set position until the said mechanism is tripped by pressure upon either side section 1.

While there is herein shown and described the preferred embodiment of the invention, it is nevertheless to be understood that minor changes may be made in the form, combination and arrangement of parts without departing from the spirit and scope of the invention as hereinafter claimed.

What I claim as new is:—

1. An artificial bird target comprising a carrier casing, a sheave within the casing, a suspension wire connected at its ends to said casing above said sheave with the intermediate portion of said wire arranged beneath the sheave whereby said carrier is effectively braced to overcome lateral swaying and a bird target body connected to said carrier casing.

2. An artificial bird target comprising a casing carrier, a bird body, means for detachably connecting the bird body to the said carrier, and means carried by said carrier for protecting its bird body connecting means while in either its set or tripped position.

3. An artificial bird target comprising a casing carrier, a bird body, means for detachably connecting the bird body to the said carrier, and plates carried by said carrier for protecting the mechanism carried by the latter while in either its set or tripped position.

4. In an artificial bird target comprising a casing carrier, a bird body, means for detachably connecting the bird body to the carrier, and depending plates swingingly carried by the casing carrier for protecting its detaching mechanism while in either its set or tripped position.

5. An artificial bird target comprising a casing carrier, hingingly connected body sections removably connected to said carrier, and means associated with said body sections for adjustably varying the outward limit of movement of the same whereby the said target may be regulated to operate under varying conditions.

6. An artificial bird target comprising a casing carrier, with extended lips to rest on the bird body between the wings, a casing below said carrier housing a locking mechanism, two leaves, one on each hinged to said casing, said leaves forming a leverage over the trippers, and a bird body the sides of which form a compound leverage over the leaves, the lower corners of which press on the inner curved surface of the bird body,

one point at each end of each leaf, making two effective points of contact on each side and two at each end, front or back so that the impact of one shot pellet anywhere, will cause the trippers to operate and cause the bird body to fall and hang suspended by the tongue, to show a kill.

7. An artificial bird target, a casing car-

rier, a casing below said carrier housing the mechanism (as herein before described) of a collapsible lock, adjustable to any degree of shot shock by means of varying number or thickness of washers at the eyes. 10

In testimony whereof I have hereunto set my hand.

EDWARD E. THRESHER.
